The ornamental design for a fastening device for antenna, as shown and described.

DESCRIPTION

FIG. 1 is a top perspective view of a fastening device for antenna according to the present invention;

FIG. 2 is a bottom perspective view thereof;

FIG. 3 is a top plan view thereof;

FIG. 4 is a bottom plan view thereof;

FIG. 5 is a left side view thereof, the opposite side being a mirror image;

FIG. 6 is a front view thereof; and,

FIG. 7 is a rear view thereof.
